UNITED STATES PATENT OFFICE.

ERCOLE H. LOCATELLI, OF NEW YORK, N. Y.

DESIGN FOR A CIGARETTE-BOX CASE.

49,066.

Specification for Design.

Patented May 16, 1916.

Application filed March 23, 1916. Serial No. 86,317. Term of patent 7 years.

To all whom it may concern:

Be it known that I, ERCOLE H. LOCATELLI, a subject of the King of Italy, residing in the borough of Manhattan, city, county, and State of New York, have invented a new, original, and ornamental Design for a Cigarette-Box Case, of which the following is a specification, reference being had to the accompanying drawing, forming part thereof.

The figure is a perspective view of a cigarette box case, showing my new design.

I claim;

The ornamental design for a cigarette box case, as shown.

ERCOLE H. LOCATELLI.
